(57) **CLAIM**

The ornamental design for a collection container for breast milk, as shown and described.

DESCRIPTION

FIG. 1 is a top, front, left perspective view of the collection container for breast milk showing our new design;

FIG. 2 is a bottom, rear, right perspective view thereof;

FIG. 3 is a front side elevational view thereof, the rear side elevational view being a mirror image thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a cross-sectional view taken along line 8-8 in FIG. 3.

1 Claim, 8 Drawing Sheets
